UNITED STATES PATENT OFFICE.

WILLIAM P. BURRIS, OF ERIE, ILLINOIS.

VENEER BRICK OR TILE.

Application filed December 13, 1924. Serial No. 755,700.

This invention relates to improvements in building bricks, and it consists of the constructions, arrangements and method of application as herein described and claimed.

5 An object of the invention is to provide a brick of such nature that it can be hung upon the exterior walls of a house or other building, thereby producing a durable and fireproof veneer which has many advantages 10 to recommend it as fully brought out below.

Another object of the invention is to provide a tile having recesses in the back for the purpose of receiving the heads of nails previously driven into a wall desired to be veneered, the tiles being made in such a way that the completed wall appears as though built of bricks.

Another object of the invention is to employ the basic principle in the construction 20 and hanging of window sills, window caps and casements.

Another object of the invention resides in the method of veneering a wall for the purpose of fireproofing, etc., and simulating a 25 brick wall.

Other objects and advantages will appear in the following specification, reference being had to the accompanying drawings, in which—

30 Figure 1 is an elevation of a window and part of a wall, illustrating the various steps in carrying out the invention.

Figure 2 is a detail perspective view of one of the veneer bricks.

35 Figure 3 is a detail perspective view of the same bricks as viewed from the rear.

Figure 4 is a detail sectional perspective showing how the nail head recess is made.

Figure 5 is a detail vertical section on the 40 line 5—5 of Figure 1.

Figure 6 is a detail horizontal section on the line 6—6 of Figure 1.

Figure 7 is a detail cross section on the line 7—7 of Figure 1 illustrating how the sill is 45 hung.

Figure 8 is a detail horizontal section of a portion of a wall illustrating how the veneer bricks join at the corner.

Figure 9 is a front elevation of one of the 50 bricks as seen from a position different from Figure 3.

Figure 10 is a similar view of the bricks showing a slight modification in the nail head recess.

55 As already briefly stated in the foregoing objects of the invention, it is intended to pro-

duce a brick that is capable of being hung upon the walls of a building, usually the exterior walls, for the purpose of making it appear as though the house were built of 60 bricks. The brick is of particular value in remodeling old frame houses, the exteriors of which are readily covered or veneered with the bricks. It is possible to produce an artistic and durable exterior by carrying forward the principle of the invention to the construction and hanging of sills, caps and casements for window and door openings. The use of the veneer brick is not confined to 70 wooden walls alone but can be hung upon old weather-worn brick buildings, concrete walls, stucco walls and stone or rock walls.

Reference is first made to Figure 1. Here the window generally designated 1 is set in a wall 2 which is presumed to consist of sheathing on the exterior. The window is composed of the frame 3 (Fig. 6), the facing 4 (Fig. 1) and sashes 5. It is immaterial whether the exterior wall be plain or consists of weather boarding which usually is 80 offset. The veneer bricks can be hung upon any kind of a surface.

Nails 6 are driven into the exterior wall at regular intervals, looking both horizontally and vertically as in Figure 1, so that the 85 heads 7 stand in position to receive the veneer bricks. It is necessary to exercise some care in the driving of the nails because if the nails are placed regularly the result will be a smooth matching of the bricks, 90 such being an obvious contribution to the artistic appearance and perfection of the work.

The brick 8 (Figs. 2, 3 and 4) is molded out of suitable plastic material. It has a 95 part 9 which, for description, is designated the brick face. This brick face may have the customary edge dimensions of an ordinary building brick (8½" by 2") or it may be of any other dimensions or proportions 100 which the particular job may require. Obviously the kinds of plastic materials of which the brick may be molded are so numerous that it is useless to endeavor to enumerate them here. The brick, for present 105 purposes, may be regarded as being made of ordinary brick clay.

The brick is offset at 10 at one side and longitudinal edge. Looking at the brick from the front (Figs. 2 and 9) the offset 10 is seen to extend to the right side of the brick face 9 and above the upper longitudinal

edge. The edge of the offset is beveled at 11 at an angle of approximately 45° , although the particular angle of the bevel may be varied. The remainder of the offset extends straight back at 12 and forms a right angle with the rear surface of the brick. That part of the brick where the offset 10 occurs may be described as a rabbet. When a number of bricks are hung (Fig. 1) the combined effect of the rabbet is so many grooves which correspond with the ordinary mortar joints in a brick wall.

Molded in the bricks 8 are one or more slots 13. These communicate with the lower edge of the bricks at a bevel 14 (Fig. 4) which corresponds in position with the longitudinal bevel 11 on the upper edge of the offset. The fact that the slot communicates with the lower bevel is merely incidental to the manufacture of the bricks. Communicating with the slot is a nail head opening 15. This has a constricted opening 16 for the occupancy of the nail shank. The slot 13 extends up a little higher than the opening 16 so that when the brick is hung upon a protruding nail, the head of the nail occupies the upper part of the slot thus locking the brick in position. The combined parts 13, 15 and 16 constitute a nail head recess.

A sill 17 is provided with a plurality of nail head recesses 18 to receive the heads 19 of nails driven into the woodwork. Inasmuch as the sill is usually quite heavy it is desirable to duplicate the nails in each instance as shown in Fig. 7. The nails are driven in one above the other, a number of sets being used so that the nail is absolutely supported. Figure 7 also illustrates the use of cement 20 for the purpose of filling openings in the joints between the sill and the adjacent veneer bricks.

The window cap 21 is constructed and hung much on the order of the sill 17. It has nail head recesses 22 which receive the heads 23 of nails driven into the woodwork for the purpose of supporting the cap.

Casement bricks 24 conceal the joints between the veneer bricks on the wall 2 and the wood facing 4 of the window frame. These casement bricks have nail head recesses 25 (Fig. 6) which receive the heads 26 of nails driven into the casing. It is noted that the mode of applying all of the various parts is identical.

Reference is next made to Figure 8. This particularly illustrates the mode of joining the veneer bricks 8 at a corner. The side edges of adjacent bricks are beveled as at 27. In hanging the bricks at corners, joints are staggered or broken, exactly as in an original brick wall. Figure 8 incidentally illustrates other internal structure of the wall which, however, has no bearing on the invention.

In Figure 10 there is a slight modification of the nail head opening 15^a. Instead of this opening being circular as in Figures 3 and 4 it is now made rectangular. This shape of opening may be desirable in some instances, but in any case it is merely for the introduction of the nail head, and in principle could be of any shape. The other brick structure is the same as that described before, and similar reference numerals designate corresponding parts without repeating the specific description.

The method of application can now readily be understood. It is the primary purpose of the veneer brick to permit remodeling exteriors of buildings. It is immaterial whether the original building be made of wood or any one of the various other materials customarily used. It is necessary only to provide for the driving in of nails 6 at regular intervals, this being necessary because the artistic appearance of the veneer will depend upon the regularity with which the bricks are hung.

It is easy to see that the nail head recesses in the back of the brick are so made that when a brick is hung in place it is prevented from coming off by virtue of the fact that the head of the nail enters the slot 13 (Figs. 4 and 5), the shank occupies the opening 16.

Provision for the drainage of moisture is made by the outward and downward inclination of the bevels 11 and 14. The bricks are hung so that these bevels engage, and being slanted as stated will serve to prevent any moisture from creeping to the rear of the veneer. The bottom and rear bevel 14 extends up the left side of the brick 8 (Fig. 9) similarly as the front upper bevel 11 extends down the right side. Reference is had to Figure 6 for this feature. The result of the bevels is that the joints between bricks are offset to the rear, all contributing toward preventing moisture from entering the backs.

The remodeling of building exteriors does not end with the treatment of walls themselves. The veneer sill 17, cap 21 and casement tiles 24 provide for transforming an otherwise plain window or door into a thing of beauty, matching the rest of the applied material. The manner of hanging the bricks is very simple, and this is also true of the manufacture thereof. The absence of loops, staples, pins, tabs, anchor bolts and the like is to be noted. The hanging element, so to speak, is cast within the brick itself, and it is necessary only to drive the necessary nails whereupon the brick can be applied immediately.

While the construction and arrangement of the improved veneer brick is that of a generally preferred form, obviously modifications and changes may be made without

departing from the spirit of the invention or the scope of the claims.

I claim:—

1. A brick having slots extending from 5 one edge to the interior, openings communicating with the slots and extending laterally to one side of the brick to receive the head of fastening means to be introduced from that side, and a narrow opening extending 10 from each head opening to receive the shank of the fastening means and thereby support

the brick, said slots extending beyond said narrow openings to admit the heads and thereby constitute a lock for holding the brick in position upon a wall. 15

2. A brick having a body with an opening in one side face thereof, said opening communicating at its upper portion with a slot 20 the base of the slot having a lateral offset to receive the head of fastening means introduced in said opening.

WILLIAM P. BURRIS.
